UNITED STATES PATENT OFFICE

98,039

DESIGN FOR A RANGE

Hans B. Hilger, Milwaukee, Wis., assignor to The Fuller-Warren Company, Milwaukee, Wis., a corporation of Wisconsin

Application April 15, 1935, Serial No. 56,392

Term of patent 3½ years

To all whom it may concern:

Be it known that I, Hans B. Hilger, a citizen of the United States, residing at Milwaukee, in the county of Milwaukee and State of Wisconsin,
have invented a new, original, and ornamental Design for a Range, of which the following is a specification, reference being had to the accompanying drawing, forming part thereof.

Figure 1 is a perspective view of a range, embodying my new design; and Figure 2 is an enlarged perspective view of a front panel of the range showing the dominant feature of the design.

The dominant feature of the design consists of two side by side alcoves or recesses set into the front panel of the range, as shown.

I claim:

The ornamental design for a range, as shown
and described.

HANS B. HILGER.
